UNITED STATES PATENT OFFICE

110,538

DESIGN FOR A PLATE OR SIMILAR ARTICLE

Paul S. Donchian, Hartford, Conn.

Application March 5, 1938, Serial No. 75,623

Term of patent 14 years

To all whom it may concern:

Be it known that I, Paul S. Donchian, a citizen of the United States, residing at Hartford, in the county of Hartford and State of Connecticut, have invented a new, original, and ornamental Design for a Plate or Similar Article, of which the following is a specification, reference being had to the accompanying drawing, forming part thereof.

Fig. 1 is a top plan view of a plate showing my new design; and

Fig. 2 is an edge view thereof.

The essential feature of my new design comprises a plate or similar article having the ornamental arrangement of stars extending around the border-portion thereof substantially as shown.

I claim:

The ornamental design for a plate or similar article substantially as shown and described.

PAUL S. DONCHIAN.
